(57) **CLAIM**

The ornamental design for a scene setter hanger, as shown and described.

DESCRIPTION

FIG. 1 is a front view of a first embodiment of a scene setter hanger; and,

FIG. 2 is a second front view of a first embodiment of a scene setter hanger.

The broken lines shown in the drawings are included for the purpose of illustrating environmental structures and form no part of the claimed design.

1 Claim, 2 Drawing Sheets

FIG. 1

FIG. 2
